Primary Examiner — Rob M Spear*Assistant Examiner* — Rashida C McCoy(74) *Attorney, Agent, or Firm* — Kenyon & Kenyon LLP**CLAIM**

The ornamental design for a shoe, as shown and described.

DESCRIPTION

FIG. 1 is a front perspective view of a shoe showing my new design;

FIG. 2 is a front view thereof;

FIG. 3 is a right side view thereof;

FIG. 4 is a rear view thereof;

FIG. 5 is a left side view thereof;

FIG. 6 is a top plan view thereof; and,

FIG. 7 is a bottom plan view thereof.

The broken line showing of the Figures is for purposes of illustration and forms no part of the claimed design.

The broken line showing of the figures illustrates unclaimed elements of the design.
